UNITED STATES PATENT OFFICE.

DANIEL MCKENZIE, OF WATROUSVILLE, MICHIGAN, ASSIGNOR OF TWO-THIRDS TO WILL N. WALTON, OF SAME PLACE, AND GEORGE REID, OF REESE, MICHIGAN.

DEVICE FOR SECURING HARROW OR CULTIVATOR TEETH.

SPECIFICATION forming part of Letters Patent No. 358,869, dated March 8, 1887.

Application filed December 23, 1886. Serial No. 222,404. (No model.)

To all whom it may concern:

Be it known that I, DANIEL MCKENZIE, a citizen of the United States, residing Watrousville, in the county of Tuscola and State 5 of Michigan, have invented a new and useful Improvement in Devices for Securing Harrow or Cultivator Teeth to Supporting-Beams, of which the following is a specification.

My invention relates to improvements in 10 devices for securing harrow or cultivator teeth to the supporting-beams; and it consists in certain novel features, hereinafter described and claimed.

In the drawings, Figure 1 is a perspective 15 view of my improved devices. Fig. 2 is a vertical section, and Fig. 3 is a horizontal section, of the same; and Fig. 4 is a detail perspective view of the coupling-plate.

Referring to the drawings by letter, A indicates a portion of one of the beams or tooth-bars of the cultivator or harrow frame, and B is the tooth secured thereto in the manner 20 which I will now proceed to describe.

The tooth B consists of a metal band bent 25 in approximately a semicircle, its lower end forming the tooth proper, or having the tooth secured thereto. The upper end of the tooth is bent upon itself to form the loop b, through 30 which the pivot pin or bolt passes, as will be presently set forth.

C is the coupling-plate. It consists of a metal plate given the proper curvature to conform to the forward rounded side of the tooth-bar A. The lower end of this plate is provided with two depending perforated lugs, c c. The distance between these lugs is just sufficient to admit the loop b on the upper end of the tooth B, which is held therein by the coupling or pivot pin or bolt D passed through 35 the said loop and the perforations in the lugs c c. The upper end of the coupling-plate is provided with two backwardly-extending wings, E, between which the end of the spring F passes, and by which it is held in place. The 40 rear side of the coupling-plate is smooth and rests against the end of the spring F. Its front side is provided about midway its ends with two ribs or ridges, G, which extend across the face of the plate, from side to side of the

same. A clip or U-shaped bolt, H, having its legs h passed through the tooth-bar in a horizontal plane, serves to secure the coupling-plate to the said tooth-bar. The shoulder or cross-bar h' of the clip passes across the face of the coupling-plate between the ribs G 55 thereon, between which it fits snugly, as shown. A washer-plate, I, is slipped over the ends of the legs h of the clip, and up against the rear side of the tooth-bar A, and nuts i on the ends of the lugs h are turned up against this washer-plate to clamp the several parts together.

The spring F, above referred to, is formed of a band of stout spring metal of the same width as the tooth B. Its upper end is passed downward between the front side of the beam and the rear side of the coupling-plate, and between the wings E, as before stated. The spring is then passed over and back of the beam, forming very nearly a semicircle, and is then turned downward, its lower end resting against the back of the tooth. A slight distance above the extreme lower end of the spring are two wings, f, projecting forward from its edges past the tooth. These wings f are perforated, and a bolt, f', is passed through 70 the perforations, serving to hold the ends of the spring to the tooth.

The operation of my device, it is thought, will be readily comprehended. As the harrow or cultivator is drawn along the ground 80 the spring presses the tooth forward, and thereby holds it to its work. Should an obstruction—such as a root, large stone, &c.—be met, the tooth will swing upward and backward upon the pivot-pin D until the obstruction is passed, when the spring will cause the tooth to at once resume its former position.

The advantages of my improved construction should be appreciated upon a casual examination. The clip H being passed through 90 the tooth-bar, its legs are protected from injury and the clip is prevented from moving from its place. After the nuts i have been turned home the parts are securely clamped together and all movement of the coupling-plate, either vertically or horizontally, is prevented by reason of the shoulder of the clip fitting snugly between the ribs G, and conse-

quently bearing directly against the inner sides thereof throughout their entire length. The tooth and the spring F are held against lateral vibration by the lugs e, the wings E and 5 the wings f. Should one part be broken it can be replaced without necessitating a renewal of any other part, for though the several parts co-operate they are entirely independent in construction.

10 I can regulate the depth of the tooth B by loosening the nuts on the arms or ends of the clip and moving the end of the spring F under the coupling-plate downward. The coupling-plate being placed in front of the beam 15 throws the tooth ahead, and thus prevents clogging.

Having thus described my invention, what I claim, and desire to secure by Letters Patent, is—

20 1. The combination, with the tooth-bar, of the coupling-plate having ribs G across its face, the tooth pivotally attached to its lower end, the spring F, having its upper end held between the tooth-bar and the coupling-plate, 25 and having its lower end connected to the tooth, and the clip or U-shaped bolt passed through the tooth-bar and across the coupling-plate between the ribs G, substantially as set forth.

30 2. The combination, with the tooth-bar, of the coupling-plate having ribs G across its

face, the tooth pivotally attached to the lower end of the plate, the spring F, having its upper end held between the coupling-plate and the tooth-bar, and having its lower end provided with the wings f, projecting forward of the tooth, a bolt passed through these wings across the face of the tooth, and the clip passed through the tooth-bar and across the face of the coupling-plate between the ribs G, to secure the several parts together, substantially as specified. 35

3. The combination, with the tooth-bar, of the coupling-plate provided at the upper end with wings E and at the lower end with lugs e, 40 and having the ribs G across its face about midway the ends, the tooth having its upper end pivotally secured between the lugs e, the spring F, having its lower end connected to the tooth and its upper end held between the coupling-plate and the tooth-bar, and between the wings E, and the clip passed through the tooth-bar and across the coupling-plate between the ribs G, substantially as described and shown. 45

In testimony that I claim the foregoing as my own I have hereto affixed my signature in presence of two witnesses.

DANIEL MCKENZIE.
